ABSTRACT: A gas lighter having a screw which is employed to perform four functions, namely, securing in position a removable baseplate, permitting the supply of a new flint without removal of the baseplate, replacement of an empty or faulty gas reservoir by a full or properly working one after removal of the baseplate, and regulation of the flame height with the baseplate secured in position.

MECHANISM FOR REGULATING THE FLAME HEIGHT IN A GAS LIGHTER

The present invention relates to mechanism for regulating the flame height in a gas lighter.

The invention relates more particularly to a special arrangement of the flint tube, which makes it possible to employ a single screw, arranged in the bottom part of said tube, in order to effect either the exchange of the flint, the exchange of the reservoir or the regulation of the flame, just as required.

A gas lighter, in accordance with the present invention, includes a flame height regulator, a detachable gas reservoir, an expansion valve carried by said reservoir, a valve lever pivoting in order to open the valve element of said valve and to allow the gas to escape, a flint contained in a flint tube, a flint wheel designed to rub against said flint in order to produce sparks and ignite the gas leaving the valve, said regulator comprising a single flint screw which is screwed into one end of the flint tube which extends through the reservoir in gastight fashion and is movable with respect to said reservoir, said flint screw acting to apply the flint against the flint wheel through the medium of a spring and to fix a detachable base in position and to regulate the flame height as a result of said movement.

In one advantageous embodiment, the flint tube is long and is fixed by a bracket between a partition which splits the body of the lighter into two portions, and a plate which forms part of a platform carried by the said partition. Preferably, the aforementioned plate forming part of said platform is apertured to permit the extension therethrough of the valve and thereby forms a shoulder with which there cooperates a shoulder on a mobile part of the valve, which part is designed to vary the pressure upon a porous washer trapped between said mobile part and a fixed part, so that when the flint screw is operated, the reservoir is moved en bloc and therefore the fixed part of the valve secured to it, thus altering the compressive pressure exerted upon the porous washer.

In accordance with another feature of the invention, on the flint screw, between its head and the end of the tube which surrounds the flint tube, there are arranged a base, a washer which bears against a boss on the detachable base of the body of the lighter, and a spring washer.

The present invention will now be more particularly described with reference to the accompanying drawings which illustrate diagrammatically one embodiment of the invention and in which:

FIG. 1 is a vertical section showing the general arrangement of the elements located in the case of a lighter in accordance with the invention;

FIG. 2 is a plan view of the underside of the lighter, that is, looking in the direction of the arrow II of FIG. 1 or FIG. 3;

FIG. 3 is a vertical section on the line III-III of FIG. 2, showing the reservoir and the bottom part of the lighter;

FIGS. 4 and 5 are vertical sections, respectively, on the lines IV-IV and V-V of FIG. 1 or FIG. 3;

FIG. 6 is an elevation sectional view of the platform portion of the present invention; and FIG. 7 is a plan view of the platform.

In these drawings, there is illustrated a gas lighter constructed in accordance with the invention and which has a case comprising a body 1 open at both ends and being rectangular in longitudinal section with the shorter sides thereof in the form of circular arcs whose diameter corresponds to the distance between the long sides (FIG. 2), a cap 2 pivotable in relation to the body 1, and a baseplate 3 (FIGS. 1 to 3) which is maintained in a seating 1a therefor at the bottom end of the body 1 in a manner which will be described hereinafter. The case is divided into two portions (FIGS. 1, 4 and 5) by a partition 4 which (as seen in FIG. 1) extends horizontally across the case and which carries a platform 5. The lower part of the case contains a detachable reservoir 6 constituted by a main portion 6a with a base and lateral walls fitting inside said lower part and a top 6b with a peripheral skirt 6c, which skirt is

located inside the portion 6a and is soldered in position. This top is shaped as at 7 to define an opening (FIG. 5) for the location of a valve 8 equipped with a wick 9 (FIG. 1, 3 and 5) which is located in the reservoir 6, and with a burner valve 5 comprising a rod 10 and a head 11 (FIGS. 1 and 5). A pivotally mounted valve lever 12 (FIGS. 1, 4 and 5) has a forked end 12a which engages the rod 10 beneath the head 11 (as seen in FIG. 5) in order to lift said head and allow the gas to pass through said valve when the user lifts the cap 2 and thereby causes said lever 12 to pivot about its pivot pin 14. A spring 13 (FIG. 4) surrounding the pivot pin 14 urges said lever 12 downwards into a position in which its forked end 12a is disengaged from the head 11 of the burner and the lever 12 is automatically raised, when the cap 2 is lifted, by a roller 15 (FIG. 4) carried on a spindle 16 in a manner which will be described hereinafter.

The cap 2 comprises a top 2a and a peripheral skirt 2b and is pivotally attached to the body 1 by a conventional kind of hinge comprising a block 17 fixed to the cap 2 (FIG. 1). One end 19 of each of two links 18 is pivotally secured to the block 17 and the other end 20 of each of said links is connected to one end of a link 21 whose other end is articulated to the spindle 16. The joint between the respective ends of the links 20, 21 is adapted to move in an elongated rectilinear slot 22 formed in the platform 5, the latter being made up of two horizontal plates 5a, 5b and two vertical cheek plates 5c connected together by a vertical portion 5d (FIGS. 1, 4-7), whilst the spindle 16 is adapted to move in elongated arcuate slots 23 in a toothed sector 24 having two arms 24a, 24b (FIG. 4) and arranged to pivot about a pivot pin 25, said sector being in constant mesh with a gear 26 fixed to a composite driver 27, 28 in which a flint wheel 29 is fixed. Said driver pivots in an opening 30 formed in the top plate 5a of the platform 5, and contains a bore 31 through which extends the upper end of a flint tube 32 containing a flint 33 and also the upper end of said flint which bears against the flint wheel 29 (FIGS. 1 and 4).

The flint tube 32 constitutes one of the features of the present invention and is very long and extends over virtually the full height of the body 1 of the lighter as can be clearly seen in FIGS. 3 and 4. Said tube 32 is fixed centrally by a collar 32a (FIG. 4) in a counterbore 34a formed in a bore 34 in the bottom plate 5b of the platform 5 and extends through the reservoir 6 within a tube 35 which is soldered in gastight fashion to the top and bottom of said reservoir, said collar 32a being held between said partition 4 and said platform 5 which are connected to one another by a screw (see FIG. 5). Furthermore, the bottom end of said tube 32 is threaded in order to coat with a flint screw 36 (FIG. 3) the top face of which acts as a seating for a flint spring 37 (FIGS. 1, 3 and 4) which forces the flint 33 against the flint wheel 29, and whose head 36a is located in a bore 38 (FIG. 1 in the baseplate 3 of the lighter body (FIGS. 2 and 3). Said bore 38 is extended, inwardly of the lighter body 1, by an annular boss 3a which is integral with said baseplate 3 and which contains an opening 38a for the extension therethrough of the screw 36 and the head 36a of a ring 39 which is slipped over said screw 36 and which bears against the bottom end of the tube 35, said bottom end projecting downwardly slightly below the level of the base of the reservoir 6, and said opening 38a being coaxial with the bore 38. A base washer 40 slipped over the stem of the base 39 bears against that part of the boss 3a which defines the opening 38a (see FIG. 3) and a thrust washer 41, for example, a spring washer or Belleville washer, is arranged between the head 36a of the flint screw and the washer 40. Said thrust washer 41 helps to keep the baseplate 3 in position in its seat 1a at the bottom end of body 1, and its loading is calculated so that the head 36a is exactly flush with the bottom face (external face) of the baseplate 3. However, at the same time, it leaves the flint screw 36 and its base 39 entirely free for rotation about its axis of rotation.

The spring 37, because of its substantial length, is centered at its bottom end by an upwardly extending spigot 36b of the

screw 36 (FIG. 3). In addition, the flint 33 does not bear directly against the opposite end of the spring, but rests against the top surface of a head 43 said head being extended downwardly to form a downwardly extending spigot 43a which centers the upper end of the spring (FIG. 3). The head 36a of the screw has a groove 44 therein (FIGS. 2 and 3) in order to enable a suitable tool (for example the edge of a coin) to be inserted for the purpose of rotating the screw about said axis in order to regulate the flame height in the manner hereinafter described.

The valve 8 is of the conventional kind and does not in itself form part of the present invention. Accordingly, only those essential elements thereof which are necessary to an understanding of its operation will be described. Said valve is located, as will be seen hereinafter, in an opening 45 in the bottom plate 5b of the platform 5 and in an opening 46 of the partition 4. As FIG. 5 shows, the body 8a of the valve is fixed in the opening which is formed in the top 6b of the reservoir 6 (for example by soldering) and contains a wick carrier 47 which acts as a thrust or compressing device and around which the wick 9 is wrapped in order to bring said wick into contact with a porous washer 48 (made, for example, of blotting paper) which is located at or in contact with the underside (as seen in FIG. 5) of an inverted gas check ring 49. Said ring 49 is capable of sliding axially in the body 8a through the medium of a seal 50 and under the action of a regulating sleeve 8b which has an annular shoulder 8c.

The wick carrier 47 is fixed and therefore the degree of compression of the porous washer 48 can be arbitrarily regulated by moving the ring 49 closer to or moving it away from the wick carrier, that is to say, by displacing the sleeve 8b axially of the body 8a.

The opening 45 in the plate 5b has a special profile which is shown in FIG. 5. It is not centered on an axis perpendicular to the plane of the plate 5b, but instead has an oblique wall which gives the valve 8 a certain degree of tilt as shown in FIG. 5. This wall has three sections 45a, 45b, 45c which define between them shoulders, of which one shoulder 45d is in contact in the assembled condition of the mechanism with the top face of the shoulder 8c, thus acting as a stop when the reservoir 6 is assembled in the case of the lighter. Accordingly, if the screw 36 were to be screwed into the tube 32 to a greater or lesser extent, the reservoir 6 would rise or descend since the head 39a of the ring 39 is constantly in contact with the end of the tube 35 soldered to the reservoir. Since the shoulder 8c is up against the shoulder 45d, if the reservoir 6 and therefore the valve 8 is lifted by rotating the screw 36 in, say, a clockwise direction, the porous washer 48 will be further compressed since the sleeve 8b cannot shift. Conversely, if the reservoir is lowered by rotating the screw 36 in an anticlockwise direction, the degree of compression of the washer 48 is reduced. It is, therefore, easy to adjust the flame to the desired height simply by rotating the screw 36 in the appropriate direction of rotation.

The general mode of operation of the lighter will now be given:

When the cap 2 of the lighter is open, springs which were tensioned in the closed condition bear against pivot 20 of the links 18 and thrust said links into their position of maximum opening, as illustrated in broken lines in FIG. 1.

However, since the link 21 is articulated at one end 20 thereof to the links 18, and at the other end thereof to the spindle 16 which can move in the curved slot 23, the movement of the pivot 20 displaces the spindle 16 in the said slot 23 into the position shown in broken lines in FIG. 1, in which the link 21, almost vertical initially, has assumed a virtually horizontal attitude. This pivoting of the link 21 has two results:

On the one hand, the toothed sector 24 pivots about its fulcrum pin 25 (see FIGS. 1 and 4) under the action of the spindle 16 moving along the slot 23, and thus moving the sector 24 and its two arms 24a and 24b to their dotted line position illustrated in FIG. 1. This movement of sector 24 causes the gear 26 to rotate, since the teeth of these two elements are con-

stantly in mesh in a generally counterclockwise direction about the axis 27a of driver carrier 27, that is, gear 26 and sector 24 move into the page, as seen in FIG. 4, at their point of engagement, indicated by the numeral 26a in the drawing. Movement of which is gear 26, keyed to the composite driver 27, 28, causes said composite driver to pivot about its axis 27a (FIGS. 1 and 4) the upper portion of driver carrier 27, on which the flint wheel carrier 28 is rotatably mounted (about the axis 28a which is offset with respect to the axis 27a) with the result that projects beyond the edge of the body of the lighter. In this position, the user's thumb can easily actuate the flint wheel carrier 28 to rotate the latter about its axis 28a, so that the flint wheel 29 rubs against the flint 33 and produces sparks which exit horizontally through a suitable opening formed in the composite driver 27, 28.

On the other hand, the roller 15 carried by the spindle 16, has as a consequence of the pivoting of the link 21, come into contact with the valve lever 12 and lifted it, as shown in broken lines in Figure 1, pivoting about the pivot pin 14 against the action of the spring 13. The rod 10 and its head 11 have thus been lifted and gas escaping from the reservoir 6 will have been enabled to pass through the head 11 of the valve and will have been ignited by the sparks produced by the friction of the flint against the flint wheel. Since the lifting of the valve lever 12 is carried out more rapidly, in practice, than the pivoting of the composite driver 27, 28, under the action of the user's thumb, it is ensured that the gas will have been liberated prior to the striking of the flint against the flint wheel and the production of sparks. Experience has shown that ignition is perfect and there is no failure.

Once the user has lit his cigarette (or generally speaking, after the lighter has been successfully used), the user will return the cap 2 to the full line position thereof shown in FIG. 1 by means of a finger; this action, associated with the weight of the cap, causes the links 18 to swing back to their dead center position and the toothed sector 26 reverts to its rest position. The valve lever 12, helped by the spring 13 again, closing the valve element of the valve 8. The downward travel of the pivot 20 tensions the aforementioned springs (not shown). Once the dead center position has passed, the pivot 20 is locked in position by the springs.

In order to exchange the reservoir, the screw 36 is unscrewed and the baseplate 3 can then easily be withdrawn and the reservoir 6 extracted. During this extracting movement, the valve lever 12, under the effect of its spring 13, pivots downwards about its pivot pin 14, disengaging the head 11 of the burner. The valve is no longer fixed in position and the reservoir can now be lifted away freely. When the full reservoir is replaced, the sleeve 8b of the valve lifts the lever 12 into the position shown in full line in FIG. 1, that is to say, to the position shown in FIG. 5. The forked end 12a surrounds the stem or neck of the burner, and when the cap 2 is opened, the lever 12 engages with the head 11 and lifts it in the manner hereinbefore described.

In order to change the flint, all that is necessary is to unscrew the screw 36 and introduce a new flint, after temporarily removing the spring 37, and there is no need to dismantle the base 3 of the lighter. It will be remembered that the flint tube 32 is fixed by its bracket 32a, between the partition 4 and the bottom plate 5b of the platform.

Finally, in order to regulate the flame height, it is merely necessary to adjust the screw 36; by doing this, the porous washer 48 is further compressed as hereinbefore described. The porosity reduces and the flame therefore tends to contract. If the screw 36 is unscrewed, however, the washer 48 is relaxed and therefore the flame height increases.

It will be seen that in accordance with the invention, the flint screw 36 fulfills four functions:

1. maintaining the pressure of the spring 37 on the flint 33 in order to apply the same against the flint wheel 29;
2. maintaining the baseplate 3 in the seat 1a in the body 1 of the lighter;

3. maintaining the reservoir 6 in position through the medium of the baseplate 3;

4. regulating the flame height.

What I claim as my invention and desire to secure by Letters Patent of the United States is:

1. In a gas lighter having an outer casing, a removable gas reservoir which is enclosed within said casing and which carries an expansion valve including fixed and movable parts enclosing a porous washer the compression of which is adjustable by a relative movement between said fixed and movable parts in order to regulate the rate of flow of said combustible gas through said porous washer, said valve being operable to permit the passage therethrough from said reservoir of a combustible gas which is ignitable by sparks produced by the rubbing of a serrated surface of a flint wheel against a flint, the improvement which consists in a flint tube extending through said reservoir in a gastight manner and secured to said outer casing; a spring housed within said flint tube; a flint supported by one end of said spring in such a manner as to protrude beyond one end of said flint tube into engagement with said flint wheel; a detachable gas lighter base and annular boss means defining an aperture in said base, which aperture is in register with said flint tube; a screw thread formed in said flint tube at the end thereof adjacent to said aperture; and a screw having an enlarged head, the diameter of which is larger than that of said aperture, said screw extending through said aperture in said base and engaging the screw thread of said flint tube not only to connect said base to the gas lighter with consequent enclosure of said reservoir but also to compress said spring with consequent pressure of said flint against said flint wheel, and said screw being in addition rotatable in said aperture in said base to cause movement of said reservoir with respect to said flint tube in one of two opposite directions at a time in order to move said movable part of the valve with respect to said fixed part for varying the compression of said porous washer and thus regulating the rate of flow of said combustible gas through the opened valve and consequently the height of the flame.

2. In a gas lighter as claimed in claim 1, a partition provided within said outer casing; means defining an aperture in said partition, said flint tube extending through said aperture; a collar extending radially outwardly of said flint tube, one axially directed face of said collar being in contact with said partition around said aperture; and a plate so shaped and apertured as to overlie said partition and said collar and to encircle said flint tube; whereby said flint tube is fixed within said outer casing.

3. In a gas lighter as claimed in claim 2, means defining a second aperture in said plate, which second aperture is in register with said valve which is carried by said reservoir; said valve having a first part thereof connected to said reservoir and a second part thereof carried by said first part, said first and second parts of said valve being movable relative to one another; means defining a shoulder in said second aperture; a shoulder on said second part of said valve; a porous element located between said first and second parts of said valve; the shoulder on said second part of the valve being in engagement with the shoulder in said second aperture; whereby rotation of said screw to cause said movement of said reservoir in one of two opposite directions at a time alters the degree of compression of said porous element with resultant regulation of the rate of flow of said combustible gas through the opened valve and consequently of the height of the flame.

4. In a gas lighter as claimed in claim 1, a dished portion of said base constituting said annular boss means defining said aperture in said base, said dished portion creating a concavity in that face of the base which in use is outwardly directed, said concavity being of a circular plan configuration and a diameter such as permits accommodation of the enlarged head of said screw said aperture in said base being of a diameter which matches that of the screw-threaded part of said screw; a second tube extending through and fixed in a gastight manner to said reservoir, said second tube being of greater inside

diameter than the outside diameter of said flint tube and being concentric with said flint tube; an assembly consisting of a spring washer, a thrust washer and a sleeve being disposed around said screw-threaded part of said screw; said sleeve having at one end thereof a portion of greater outside diameter than that of the remainder of said sleeve; said spring washer and said thrust washer encircling a part of said remainder of said sleeve with the thrust washer located between said portion of greater outside diameter and said spring washer; said thrust washer being of greater outside diameter than that of said aperture in said base; the other end of said sleeve being in contact with said enlarged head of said screw and said portion of great diameter being in contact with one end of said second tube; whereby rotation of said screw to increase the degree of compression of said porous element by moving the reservoir away from said base results in compression deformation of said spring washer as a consequence of said enlarged head of said screw being drawn axially towards said thrust washer which is itself drawn axially inwardly of the gas lighter against said dished portion of said base.

5. In a gas lighter having a lighter body which is open at both ends, a cap hingedly mounted upon said body at one of said ends, a base connected to said body at the other of said ends; means defining an aperture in said base; said lighter body, said cap and said base defining a cavity; a cavity divider dividing said cavity into two parts; a gas reservoir removably located in one of said two parts of said cavity; an expansion valve having a first part thereof connected to said reservoir and having a second part thereof carried by said first part; said first and second parts of said valve being movable relative to one another; said second lever-operated element movable in one direction of movement thereof to permit the passage of gas through said valve from said reservoir; means in said cavity divider defining an aperture and an abutment; said second part of said valve extending into and through said aperture and also engaging said abutment; spark-producing means including a flint and a serrated surface on a flint wheel; a flint tube and spring means therein, said spring means acting when compressed to press said flint into engagement with said serrated surface in the vicinity of one end of said tube; said flint tube extending through said reservoir in a gastight manner; and a single screw-threaded device engaged with and extending into the other end of said tube and thereby connecting said base to said body and thereby also enclosing and maintaining said reservoir within said one of said two parts of the cavity and thereby also compressing said spring means to press said flint against said serrated surface, rotation of said device causing said first and second parts of said valve to move relative to one another to alter the amount of gas which will pass through the valve upon movement of said element in said one direction of movement.

6. In a gas lighter having a lighter body adapted to receive a gas reservoir therein and an expansion valve having first and second parts movable with respect to each other, means for regulating the rate of flow of gas through said valve comprising, a flint tube adapted to receive a flint and biasing spring therefore extending through said reservoir and having an internally threaded end portion adjacent the base of said reservoir, and means threadably engaged with said end portion for compressing said spring between said screw and said flint and operably engaged with said reservoir for moving said first and second valve parts with respect to each other to regulate the rate of gas flowing therethrough.

7. In a gas lighter having a flint wheel and a lighter body adapted to slidably receive a gas reservoir therein having an expansion valve including fixed and movable parts, means for regulating the rate of flow of gas through said valve comprising, a flint tube adapted to receive a flint and a biasing spring therefore, said flint tube extending through said reservoir and having an internally threaded end portion adjacent the base of said reservoir, a screw threadably engaged with said end portion for compressing said spring and urging said flint into engagement with said flint wheel, said screw being operably en-

gaged with said reservoir for moving said reservoir and said movable valve part with respect to said fixed valve part upon rotation of the screw to regulate the rate of gas flowing through said valve.

8. A device as defined in claim 7 wherein said screw includes a head portion operably engaged with the base of said reservoir.

9. A device as defined in claim 8 wherein said expansion valve includes a porous washer positioned between said movable and fixed valve parts, whereby movement of said movable valve part with respect to said fixed valve part varies the compression of said porous washer to regulate the flow of gas through said valve.
